FIG. 3

FIG. 5

FIGURE 1 is a perspective view of a seat belt retractor, showing our new design; the dotted lines shown being for illustrative purposes only;

FIGURE 2 is a bottom plan view, it being understood that the broken line showing of the spring extends throughout the spring housing;

FIGURE 3 is a cross-sectional view taken generally along line 3—3 of FIGURE 2;

FIGURE 4 is a front elevational view of the seat belt retractor shown in FIGURES 1-3; and

FIGURE 5 is a rear elevational view illustrating the seat belt retractor shown in FIGURES 1-4.

The dominant features of our design reside in the portion shown in full lines.

We claim:

The ornamental design for a seat belt retractor, substantially as shown and described.
